UNITED STATES PATENT OFFICE

JOSEF ENGL, OF BERLIN-GRUNEWALD, GERMANY, ASSIGNOR TO ENGL PRODUCTS CORPORATION, OF NEW YORK, N. Y., A CORPORATION OF NEW YORK

AMPLIFYING SYSTEM

Application filed June 19, 1930, Serial No. 462,199, and in Germany February 4, 1929.

An application for this invention has been filed in Germany, Feb. 4, 1929.

My invention relates to amplifying systems including a plurality of vacuum tubes.

5 My invention relates particularly to a system of the character described wherein distortion of the amplified current is less than exists with prior arrangements.

10 Various other objects, advantages and characteristics of my invention will become apparent from the following detailed description taken in connection with the accompanying drawings.

15 My invention resides in the system, circuit arrangements and features of the character hereinafter described and claimed.

20 For an understanding of my invention and for an illustration of some of the various forms thereof, reference is to be had to the accompanying drawings, in which:

Figs. 1 and 2 are graphical views of current oscillations; and

25 Fig. 3 is a diagrammatic view of an amplifying system arranged in accordance with my invention.

It is known in the art that the anode circuit of each vacuum tube in an amplifying system may include an ohmic resistance or a choke coil and that, upon occurrence of current

30 variations in an anode circuit of any given tube, voltage fluctuations result between the cathode and anode of that tube, such voltage fluctuations being due to the varying voltage drop across the aforesaid ohmic resistance or to the inductance of the choke coil, as the case

35 may be. With the grid of the next succeeding amplifying tube connected to the anode of the aforesaid given tube through a coupling capacity, it has been customary to place

40 a high ohmic resistance, known as a leakage resistance, between the grid and cathode of said succeeding amplifying tube, for example, in series with the grid biasing battery, or equivalent, and serving to give a favorable working potential to the grid of said succeeding amplifying tube.

45 As regards the values of the aforesaid coupling capacity and leakage resistance, the following holds true: As large a fraction as possible of the alternating voltage produced

by said given amplifying tube should become effective between the cathode and grid of said next succeeding amplifying tube. For this purpose and for the frequency to be amplified, the impedance of the coupling condenser, 55 which at a frequency f and with a capacity C of the coupling condenser has the value

$$W_J = \frac{1}{2\pi f C} \quad 60$$

must be small. Preferably, it amounts to $\frac{1}{10}$ of the leakage resistance, and 90% of the alternating voltages produced in said given amplifying tube act upon the next succeeding amplifying tube. If this relation is used as a basis for the choice of the coupling capacity and the ohmic leakage resistance for each frequency, there results for the time constant T of the discharge of the coupling condenser, 70 which as is known is equal to the product of the coupling capacity C and the leakage resistance w , a figure, which is dependent on the frequency and which is proportionately large for small frequencies. 75

If the impedance of the coupling condenser is $\frac{1}{10}$ of the leakage resistance w , then

$$\frac{1}{2\pi f C} = 0.1 \cdot w \quad 80$$

which gives

$$\frac{10}{2\pi f} = w \cdot C = T$$

This equation shows, for example, that for 85 the frequency

$$f = \frac{100}{2\pi}$$

there is obtained for the time constant the 90 proportionately large amount of 0.1 second. This signifies the following for the mode of operation of amplifying systems of this kind:

If these amplification stages are fully modulated by a higher frequency, for example, $f=1000$, the coupling capacity as a consequence of the large time constant of the combination does not have time to discharge again. The consequence of this is that the mean grid bias changes and, therefore, the 95

amplification stage at this high frequency is overmodulated.

In accordance with my invention, the disadvantage thus recited as arising in connection with capacity-coupled amplifying tubes is overcome by using a choke coil as leakage resistance for the last amplifying stage, the direct current resistance of said choke coil being so small that, together with the coupling capacity, there results a time constant which does not exceed approximately 0.001 of a second. Since the impedance of the choke coil may be large despite its low direct current resistance, it results that good efficiency of operation, especially at low frequencies, is obtained for the tube forming said last named amplifying stage.

Referring to the drawings, Figs. 1 and 2 show graphically the modulation process of the anode current in the last amplifying stage at a high frequency where $f=1000$, for example, which is the case where the time constant of the combination—coupling capacity and leakage resistance—is too large. As shown, the mean anode current immediately rises and an oscillation supplied in sine form in the anode circuit, Fig. 1, ceases to have the sine form since substantial distortion takes place as shown in Fig. 2.

In general, the foregoing action occurs in the anode circuit of the last tube of an amplifying system. However, in many cases, it may occur, in the event of appearance of sufficiently large modulation amplitudes, in a preceding tube, for example, the last tube but one, of the amplifying system. Ordinarily, with all tubes of the system, except the last two tubes, this phenomenon does not occur since, with them, the controllable range is large in contrast with the modulation amplitudes.

For purposes of further explanation of my invention, there is illustrated in Fig. 3 a vacuum tube amplifying system of a particular type although it shall be understood that my invention is applicable as well to other types of vacuum tube amplifying systems.

As shown, a plurality of vacuum tubes V, V1 and V2 are utilized to form the last three stages of a multistage amplifying system, the individual stages being connected to one another in any suitable manner, as, in the known way, by the coupling resistances 1, 2 and 3 together with the coupling capacities 4, 5 and 6.

The filaments of the aforesaid tubes and the anode circuits thereof may be energized in any suitable manner; similarly, the temporarily necessary grid biasing potentials may be obtained in any suitable manner. As illustrative of a simple arrangement, there is herein shown a filament battery 7, a common anode circuit battery 8, and the batteries 9, 10 and 11 for applying a biasing potential to the grids of the respective tubes

V, V1 and V2, all of said batteries being connected in proper circuit relation as well understood in the art. It shall be distinctly understood that any other suitable energizing and grid-biasing arrangement may be utilized in lieu of that just described.

In accordance with usual practice, the grid circuit of the vacuum tube V includes an ohmic leakage resistance 12 and, in accordance with my invention, the grid circuit of the vacuum tube V2 includes a choke coil 13 of low ohmic resistance. Further, in accordance with my invention, the grid circuit of the vacuum tube V1 may include a choke coil 14 also of low ohmic resistance although the use of said last named choke coil is optional under some circumstances. The choke coil 13 and the choke coil 14, when utilized, eliminate or substantially eliminate the possibility of insufficient discharge of the coupling condensers 5 and 6 at high frequencies. Due to this fact, the otherwise resultant distortions are eliminated with resultant great improvement in the characteristics of the anode circuit current in the vacuum tube V2.

In order to obtain a desired or satisfactory degree of amplification, the impedance of the aforesaid choke coils 13 and/or 14 may be made adjustable in any suitable manner. To this end and as shown the choke coil 13 may comprise a plurality of windings, one of which is connected to a suitable source of direct current whereby, by a premagnetizing action, the choke coil impedance may be varied in a desired adjustable manner. The choke coil 14, when utilized, may be similarly equipped with a supplementary winding to which a source of current is connected.

Furthermore, to obtain a higher impedance with but few windings, one or both of the choke coils 13 and 14 may be provided with a core or cores of magnetic material preferably having high initial permeability, such as permalloy or other materials of similar properties.

Still further, the choke coil core, when utilized, may be made adjustable or displaceable whereby the choke coil impedance may be readily adjusted.

It shall be distinctly understood that my invention contemplates the utilization of a choke coil, or equivalent, for but one of the vacuum tubes, usually the last stage vacuum tube, of the amplifying system although, if desirable and necessary, one or more of the preceding amplifying tubes may be similarly equipped.

While the invention has been described with respect to certain particular preferred examples which give satisfactory results, it will be understood by those skilled in the art after understanding the invention, that various changes and modifications may be made without departing from the spirit and scope of the invention and it is intended therefore

in the appended claims to cover all such changes and modifications.

What is claimed as new and desired to be secured by Letters Patent is:

- 5 1. In an amplifying system, a plurality of vacuum tubes, a connection including a capacity coupling between the anode of one tube and the grid of the next succeeding tube, a leakage path connected to said connection,
- 10 said leakage path including a choke coil of relatively low ohmic resistance and high impedance, and a core of magnetic material for said choke coil, said core being of high initial permeability and adjustable whereby
- 15 the impedance of said choke coil may be adjusted.
- 20 2. In an amplifying system, a plurality of vacuum tubes, a connection including a capacity coupling between the anode of one tube and the grid of the next succeeding tube, a leakage path connected to said connection, said leakage path including a choke coil, and a magnetizing coil inductively related to said choke coil.
- 25 3. In an amplifying system, a plurality of vacuum tubes, a connection including a capacity coupling between the anode of one tube and the grid of the next succeeding tube, a leakage path connected to said connection,
- 30 said leakage path including a choke coil, a magnetizing coil inductively related to said choke coil, and a source of direct current connected to said magnetizing coil.

In testimony whereof I have signed my name to this specification.

JOSEF ENGL.
